UNITED STATES PATENT OFFICE.

AMAN G. BROUSSARD, OF BREAUX BRIDGE, LOUISIANA.

TEST-DRILL.

1,224,847.

Specification of Letters Patent.

Patented May 1, 1917.

Application filed November 14, 1916. Serial No. 131,323.

To all whom it may concern:

Be it known that I, AMAN G. BROUSSARD, a citizen of the United States, residing at Breaux Bridge, in the parish of St. Martin 5 and State of Louisiana, have invented new and useful Improvements in Test-Drills, of which the following is a specification.

This invention relates to an improved device which may be properly called a test 10 drill and which is utilized for obtaining specimens of soil formation at various depths when drilling prospect holes, oil wells and the like.

The invention has for its object to produce a simple and improved device which 15 may be operated at the end of a string of pipe, the same as an ordinary drill, but the said device being adapted to take specimens of the soil formation at any depth and to 20 inclose the same so that said specimens will be preserved without contamination while being elevated to the surface of the ground.

A further object of the invention is to produce a test drill having a valve equipment 25 enabling it to be washed and cleansed thoroughly before taking the desired specimen, being thereby free from any substances which may have accumulated therein during the descent into the hole.

30 A further object of the invention is to simplify and improve the construction of the valve equipment which forms a part of the device.

With these and other ends in view which 35 will readily appear as the nature of the invention is better understood, the same consists in the improved construction and novel arrangement and combination of parts which will be hereinafter fully described 40 and particularly pointed out in the claims.

In the accompanying drawings has been 45 illustrated a simple and preferred form of the invention, it being, however, understood that no limitation is necessarily made to the precise structural details therein exhibited, but that changes, alterations and modifications within the scope of the claims may be resorted to when desired.

In the drawings,—

50 Figure 1 is a view in side elevation of a device constructed in accordance with the invention.

Fig. 2 is a vertical sectional view taken on the line 2—2 in Fig. 1.

55 Fig. 3 is a vertical sectional view on a

larger scale of the valve device and the collar or casing in which the same is housed.

Fig. 4 is a horizontal sectional view taken on the line 4—4 in Fig. 3.

Fig. 5 is a top plan view of the valve 60 device removed from the casing.

Fig. 6 is a bottom plan view of the same.

Fig. 7 is a horizontal sectional view, enlarged, taken on the line 7—7 in Fig. 1, and showing the specimen chamber open.

65 Fig. 8 is a similar view showing the chamber closed.

Fig. 9 is a horizontal sectional view taken on the line 9—9 in Fig. 1.

Fig. 10 is a horizontal sectional view taken 70 on the line 10—10 in Fig. 1.

Corresponding parts in the several figures are denoted by like characters of reference.

The drill bit 15, which may be of the diamond, fish tail or any other approved type, 75 is fixed at the lower end of a tube 16 which is revolubly fitted within an outer tube 17 where it is secured by means of a pin or screw 18 extending transversely there- 80 through, the ends of said pin or screw engag- ing diametrically opposed slots 19 in the outer tube, whereby the rotary move- ment of the tube 16 is limited with respect to said outer tube, while longitudinal move- 85 ment of the inner tube with respect to the outer tube is prevented. The inner and outer tubes 16, 17 are respectively provided with longitudinal slots 20, 21 which, by par- 90 tial rotation of one tube with respect to the other, may be placed in or out of registry, thereby permitting or preventing access of material to the inner tube, as the case may be. One side wall of the slot 21 in the outer tube 17 is bent outward and sharpened to 95 form a cutting or scraping member 22 whereby, when the device is rotated about its vertical axis, material may be scraped or forced through the slots 21, 20 into the compartment or receptacle formed by the inner tube. The said tube is closed at its 100 lower and upper ends, said upper end portion being, however, provided with an axial aperture 23.

The outer tube 17 is externally threaded at its upper end for engagement with a collar 24, said collar receiving at its upper end a tubular nipple 25 having bleed holes 26, said nipple being connected at its upper end with the string of pipe, a portion of which is seen at 27.

The collar 24 is internally threaded throughout its length in order that it may be terminally connected with the tube 17 and the nipple 25 and also for the reception 5 of an externally threaded plug 28 through which extends an axial threaded stem 29 on which the said plug may be regarded as being adjustably mounted; that is to say, by rotating the said stem relative longitudinal 10 axial adjustment of the stem and the plug may be effected. Valve disks 30, 31 are seated on the top and bottom faces of the plug 28, the upper valve disk being seated gravitationally and the lower valve disk being held seated by means of a spring 32 coiled about the stem 29 and abutting at its lower end on a stop member, such as a nut 33. A guide pin 34 extends through the plug with which it is fixedly connected and 15 through the respective valves which are thereby prevented from turning about the axis of the stem 29. The plug is provided with ports or apertures 35, 36 that register, respectively, with ports or apertures 37, 38 20 in the upper and lower valve disks 30 and 31. It will thus be seen that while the port in the top disk 30 constantly communicates with the upper end of the port 35, the lower end of said port 35 is obstructed by the bottom valve disk 31, while on the other hand the port 38 in the bottom valve disk is constantly in communication with the port 36, the upper end of which is obstructed by the upper valve disk. Access to the interior of 25 the tube 16 through the aperture 23 at the upper end thereof may thus be regarded as being normally obstructed by the valve device just described.

In the use of the improved device, it is 30 connected with the lower end of a string of pipe that is used for drilling purposes, and when the bottom of the hole is reached and the bit 15 has become partly embedded, the outer tube 17 is turned in the proper direction to bring the slots 20, 21 into registry. The drill hole is now to be cleansed from the impurities which may have accumulated at the bottom thereof, and this is effected by 35 injecting liquid under pressure through the drill pipe, the pressure being sufficient to cause the valve 31 to open against the tension of the spring 32, the injection of liquid being continued until the hole is clean. This, of course, will leave liquid standing 40 in the lower portion of the drill pipe, below the valve device, and particularly within the tube 16. The drill is now started and by the operation thereof the material loosened by the drill is scooped by the cutter or 45 scraper 22 through the slots 20, 21 into the compartment formed by the inner tube 16, the liquid contained in said tube and in the lower portion of the drill tube being displaced upwardly through the aperture 38 in 50 the lower valve disk 31 and through the port

36, the gravitationally seated upper valve disk 30 yielding to the upward pressure of the liquid which is being displaced. When the operator judges that a sufficient quantity of specimen stuff has been accumulated 55 within the tube 16, the rotation of the drill tubing is reversed, causing the outer tube 17 to rotate about the tube 16 in the proper direction to close the opening in the wall thereof. The drill may now be withdrawn 60 from the drill hole, and as it is being withdrawn the valve device will effectually obstruct communication between the compartment formed by the tube 16 and the tubing above the same. Any water or liquid contained in the drill tubing will escape 65 through the bleed holes 26, thus enabling an uncontaminated specimen to be obtained.

In the drilling of oil wells and other wells it is extremely desirable and important to 70 obtain specimens of soil formation at various depths, especially when an oil or mineral bearing stratum is reached, in order that further operations, such as the setting and location of screens, the determining of 75 the mesh of said screens and other matters may be decided with a view to bringing about the most successful results. By the improved device an exact and uncontaminated specimen of the soil formation at any 80 determined depth may be obtained, thereby affording a safe guide to the operator for further proceedings.

Having thus described the invention, what is claimed as new, is:—

1. In a device of the class described, an inner tube carrying a bit, an outer tube in which the inner tube is mounted for limited rotary movement, and a stop member limiting such rotary movement and preventing 105 the relative longitudinal movement of the inner and outer tubes, said tubes having longitudinal slots which by partial rotation of one tube may be placed in and out of registry, a side wall of the outer tube being 110 provided with a projecting cutting and scraping member; in combination with a valve device supported above the outer tube, said valve device being adapted to permit passage of liquid under pressure upwardly 115 and downwardly.

2. In a device of the class described, a valve device comprising a plug having two ports extending vertically therethrough, a stem on which the plug is mounted, valve 120 disks seating on the two ends of the plug and having apertures alining with the respective ports, a guide pin extending through the plug and the valve disks to prevent axial rotation of the latter, and a spring 125 whereby the bottom valve is normally held seated.

3. In a device of the class described, a valve device comprising a plug having two ports extending vertically therethrough, a 130

- stem on which the plug is mounted, valve disks seating on the two ends of the plug and having apertures alining with the respective ports, a guide pin extending through the plug and the valve disks to prevent axial rotation of the latter, and a spring whereby the bottom valve is normally held seated, the axial stem being longitudinally adjustable with respect to the plug.
5. In a device of the class described, an inner tube carrying a bit, an outer tube in which the inner tube is fitted for rotation, said outer tube having diametrically opposed slots, a stop pin extending through the inner tube and engaging the slots to limit the rotary movement of the inner tube, said inner and outer tubes having longitudinal slots that may be placed in and out of registry by rotary movement of one tube, a nipple having bleed openings, a collar connecting the nipple with the outer tube, and a valve device housed in the collar, said valve device comprising a plug having vertical ports extending therethrough, valve disks seated on the top and bottom faces of the plug and having apertures registering with the respective ports, means whereby rotary movement of the valves will be prevented, and a spring whereby the bottom valve is normally maintained in seated condition.
10. 4. In a device of the class described, a valve device comprising a plug having two ports extending vertically therethrough, a stem on which the plug is mounted, valve disks seating on the two ends of the plug and having apertures alining with the respective ports, a guide pin extending through the plug and the valve disks to prevent axial rotation of the latter, and a spring whereby the bottom valve is normally held seated, the axial stem being in threaded engagement with the plug for longitudinal adjustment with respect thereto, and said stem being provided with a stop member forming an abutment for an actuating spring for the bottom valve.
